CLAIM

The ornamental design for an electronic novelty game, as shown and described.

DESCRIPTION

FIG. 1 is a perspective view of our new design for an electronic novelty game;

FIG. 2 is a top view thereof;

FIG. 3 is a bottom view thereof; and,

FIG. 4 is a front view thereof, the rear view and right and left side views being essentially identical to the front view.

1 Claim, 4 Drawing Sheets

FIG. 1

FIG. 2

FIG. 4
